UNITED STATES PATENT OFFICE.

HENRY C. LEWIS, OF MILLER TOWNSHIP, PENNSYLVANIA.

IMPROVED RAILROAD-SWITCH.

Specification forming part of Letters Patent No. **71,769**, dated December 3, 1867.

To all whom it may concern:

Be it known that I, H. C. LEWIS, of Miller township, in the county of Perry, and in the State of Pennsylvania, have invented certain new and useful Improvements in Railroad-Switch; and do hereby declare that the following is a full, clear, and exact description thereof, reference being had to the accompanying drawings, and to the letters of reference marked thereon.

The nature of my invention consists in the peculiar arrangement and connection of the several rails which form the switch for more especially dispensing with the use of frogs, as will be hereinafter described.

I construct and arrange the ends of the rails which form the switch so that they meet properly to form a continuous railroad-track, according to the direction it is designed to have the track and the cars run. The switch-rails have one end permanently secured to the tie, while their other ends are secured in openings formed in an iron bar, so that they cannot spread, and so that they may be moved simultaneously.

M N O P represent the bars in which the switch-rails lie, which said bars run to the switch-posts *q q*, and are operated by the levers R R. J and K represent two of the switch-rails, G and D represent two, and E and F represent two. These movable rails connect with stationary rails, and are shifted to suit the nature of the case, either to run cars to a switch or to continue them upon the main track.

Having thus fully described my invention, what I claim as new, and desire to secure by Letters Patent, is—

The chains provided with bolts which pass into cross-ties for securing the rails J K, and allow the same to be moved laterally, as and for the purposes set forth.

In testimony that I claim the foregoing I have hereunto set my hand and seal this 19th day of April, 1867.

HENRY C. LEWIS.
